SHOE

Charles Tweedie, Jefferson City, Mo.

Application October 6, 1941, Serial No. 413,715

2 Claims. (Cl. 112—262)

My invention relates to the problem of sewing two pieces of sheet material together in edgewise relation and especially with the problem of uniting an elastic webbing tape to the top edge of the main stretchable member of a shoe upper. Its principal objects are to devise a reinforced system of stitching that will hold the abutting edges of the material together tight, and which will prevent gapping of the abutting edges and will minimize the danger of tearing or fraying of the material and which also will permit longitudinal stretching of the seam. The invention consists principally in a seam construction of the lock stitch type that comprises three rows of stitches made with a single needle thread and a single bobbin thread, the stitches in each row being disposed in zigzag relation to each other and being staggered with relation to the stitches of the adjacent row and with the stitches of the middle row extending across the abutting edges of the pieces to be united. It also consists in the application of this system of stitching for uniting an elastic webbing tape to a shoe upper member in edgewise abutting relation, especially where such upper member is made of stretchable leather or elasticized material.

In the accompanying drawing which forms part of this specification and wherein like symbols refer to like parts wherever they occur,

Fig. 1 is a perspective view of a shoe embodying my invention,

Fig. 2 is an enlarged fragmentary face view of the shoe upper in the region of the foot opening; and

Fig. 3 is a cross-sectional view on the line 3—3 in Fig. 2.

Where two pieces of sheet material are to be sewed together, it is the usual practice to have the margin of one piece lap the margin of the other and to have the needle pierce the material as far back from the edge of the material as may be necessary to prevent tearing or fraying of the material in service. This practice results in the lapping or folding back of the margins of the material, with the lapped or folded material forming ribs that may be quite objectionable, especially in footwear. By sewing the pieces together in edgewise abutting relation, formation of such objectionable ribs may be avoided and smaller pieces of material are required than are required in the present common practice; but, in such case the requisites of the stitching are more exacting, especially when the material is stretchable.

According to the present invention, the two pieces to be united are fed in edgewise abutting relation to the stitching mechanism of a lock-stitch sewing machine which is equipped with a needle that vibrates or swings crosswise of the longitudinal line of the material and is adapted to form a group X of three stitches 1, 2, 3 extending crosswise in one direction followed immediately by a group Y of three stitches 4, 5, 6 extending crosswise in the opposite direction and so on back and forth, all of the stitches being oblique with respect to the line of feed and being disposed in three longitudinal rows, namely, a middle row A and two side rows B, C.

15 The three stitches of each transverse group are made in direct succession and are arranged in zigzag relation to each other, that is, the inclination of the middle stitch of a transverse group is in the opposite direction to that of the outer 20 stitches of the same transverse group. The stitches in each longitudinal row are disposed zigzagwise, that is, with alternate stitches inclining in opposite directions. Each of the outer stitches of each transverse group meets at an 25 angle the adjacent stitch in the same longitudinal row. The general pattern of the stitching may be considered as made up of two rows of diamonds or squares with the stitches of the middle row constituting sides that are common to 30 the diamonds of both rows.

On account of the stitches of a transverse group being of an odd number and disposed zigzagwise, the first-formed endmost stitch of each 35 transverse group follows immediately after the last-formed stitch of the preceding transverse group, while the last-formed endmost stitch immediately precedes the first-formed stitch of the next following transverse group. Thus, the point of beginning of the first stitch of a transverse group is the width of said group in advance of 40 the end point of the last stitch of said group.

45 Six stitches are made in each cycle of operation. For instance, beginning with stitch 1 in outer row B, the sequence is: stitch 2 in middle row A, stitch 3 in outer row C, stitch 4 in outer row C, stitch 5 in middle row A and stitch 6 in outer row B, stitches 1, 2 and 3 being in transverse group X and stitches 4, 5 and 6 being 50 in transverse group Y, and the point of beginning of any cycle being spaced from the point of beginning of the next cycle by a distance equal to the sum of the widths of the two transverse groups of stitches X and Y. Preferably, in forming 55 the inner ends of the outer or anchor stitches,

the needle passes through the same hole used in making the ends of the inner stitches.

In applying the system of stitching above described, the two pieces D, E of material to be joined, say, a piece of stretchable leather or elasticized material constituting the main member D of a shoe upper and a piece of elastic webbing tape E are fed to the stitching mechanism in edgewise abutting relation and in such position that the stitches of the middle row A extend across the abutting edges of the two pieces with their ends anchored to said pieces respectively. The stitches of one outer row C are anchored entirely in one of the pieces of material, say the main member D of the upper, and the stitches of the other outer row B are anchored entirely in the other piece, namely, the tape E. In the shoe F illustrated in the drawing, one of the pieces is the main member D of the upper of the shoe and the other piece E is a strip of elastic extending along the foot opening and united to said main member in edgewise abutting relation with the stitches of the middle row extending across the abutting edges of said main member and said elastic strip.

The outer row of stitches are not merely ornamental; they serve important mechanical functions. Thus, in making the middle stitch, it may happen occasionally that the needle may pierce the material so close to its edge that the material is liable to tear or fray under a transverse stress arising from ordinary conditions of service. With my system of stitching, a considerable portion of the transverse stress on the middle stitch is transmitted to one or both of the two adjacent stitches in one or both of the outer rows. In this way, the unit stress on the material is greatly lessened and a considerable portion of the total stress is applied at points where the material is amply able to resist it. In case the needle should cut the edge of the material,

which heretofore would have entailed liability to gapping of the seam and probably involved the scrapping of the work, especially when leather is used, my system of stitching prevents gapping of the seam and avoids such scrapping because each end of a middle stitch is guyed or steadied by two outer rows of stitches converging at said end. For a similar reason, any tendency of the material to lap or wrinkle endwise due to stretching is minimized.

What I claim is:

1. A shoe comprising an upper material having a strip of elastic material secured thereto in edgewise abutting relation by a single line of stitching 15 consisting of successive transverse zones of three stitches each that extend from one side of the abutting edges of said materials to the other side of said abutting edges, each of said transverse zones including substantially parallel outer 20 stitches located directly opposite each other one on each side of said abutting edges and disposed at oblique angles thereto and a middle stitch connecting said outer stitches and extending at a reverse oblique angle thereto across said abutting edges, the corresponding stitches of alternate transverse zones inclining in opposite directions, each of the outer stitches of each transverse zone converging toward and meeting the outer stitch of an adjacent transverse zone at 25 30 the outer end thereof.

2. A shoe comprising an upper material having a strip of elastic material secured thereto in edgewise abutting relation by a single line of stitching 35 consisting of three zones of stitches arranged zigzagwise longitudinally of the abutting edges of said material to form two interlocking longitudinal rows of closed diamonds with the stitches of the middle zone uniting the upper material to the strip of elastic material and constituting the 40 inner sides of the diamonds of both rows.

CHARLES TWEEDIE.
